(57) **CLAIM**

The ornamental design for a hearing aid set, as shown and described.

DESCRIPTION

FIG. 1 is a front perspective view of the right side hearing aid;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof of the left side hearing aid;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view of the case;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a perspective view showing both the left and right side hearing aids;

FIG. 26 is a perspective view showing the hearing aid set in an open state; and,

FIG. 27 is a perspective view showing the hearing aid set in a closed state.

The broken lines in the drawings illustrate the portions of the hearing aid set, which form no part of the claimed design.
